Primary Examiner — Mark Goodwin(74) *Attorney, Agent, or Firm* — Lathrop & Gage L.L.P.**CLAIM**

The ornamental design for an off-highway work vehicle, as shown and described.

DESCRIPTION

FIG. 1 is a perspective view of an off-highway work vehicle in accordance with the principles of the present disclosure.

FIG. 2 is a left side view thereof.

FIG. 3 is a right side view thereof.

FIG. 4 is a front view thereof.

FIG. 5 is a back view thereof.

FIG. 6 is a top view thereof; and,

FIG. 7 is a bottom view thereof.

The broken line showing of a work vehicle is included for the purpose of illustrating environmental structure only and forms no part of the claimed design.

1 Claim, 7 Drawing Sheets(56)
